(57) **CLAIM**

The ornamental design for a signal converter, as shown and described.

DESCRIPTION

FIG. 1 is a perspective view of a signal converter embodying the inventive ornamental design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines of FIG. 7 are included for the purpose of illustrating environmental structure and form no part of the claimed design.
